UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT STOCK COMPANY OF FRANCE.

MULTIBARREL GUN.

Application filed January 4, 1924. Serial No. 684,420.

To all whom it may concern:

Be it known that I, EUGÈNE SCHNEIDER, a citizen of the Republic of France, residing at Paris, France, have invented new and 5 useful Improvements in Multibarrel Guns, which is fully set forth in the following specification.

This invention has for its object to provide an improved multi-barrel gun. This 10 improved gun is characterized by the conjugation of its barrels in pairs or in groups each comprising an even number of barrels. The conjugation is such that a portion of the energy due to the recoil of one barrel 15 or one group of barrels, is utilized in a suitable recuperator for running-out the other barrel or group of barrels of the conjugation, and vice versa. This conjugation allows of maintaining an approximately 20 constant position of the centre of gravity of the whole of the movable parts of the gun during firing. Part of the energy of the recoil may nevertheless be utilized for effecting automatic operation of the breech mechanism or mechanisms, the loading device or 25 devices, and also, if required, of the firing mechanism or mechanisms.

The invention will be readily understood by reference to the accompanying drawings, 30 illustrating two embodiments of the inventive idea, and wherein:

Fig. 1 is a cross section of two conjugated gun barrels illustrating one embodiment of the present invention.

Figure 2 is a horizontal section taken 35 along the line 2—2 of Figure 1, viewed from underneath, showing the two barrels in one position of operation.

Figure 3 is a similar horizontal section 40 showing the barrels in another position of operation.

Fig. 4 is a side elevation of another constructional form of the invention;

Fig. 5 is a transverse sectional view illustrating the brake mechanism and recuperator shown in Fig. 4;

Fig. 6 is a horizontal section taken along 50 the line 6—6 of Fig. 5 viewed from underneath, the conjugated parts being shown in a position of rest;

Figs. 7 and 8 are similar sectional views showing the parts in the position they oc-

cupy during two successive phases of their working when one of the barrels is fired;

Fig. 9 is a horizontal section taken on the line 9—9 of Fig. 5;

Fig. 10 is a longitudinal sectional view, somewhat enlarged, illustrating more clearly the details of the braking cylinders.

Referring to the drawings, wherein like reference characters refer to like parts throughout the several views, and particularly to Figs. 1 to 3 inclusive, two gun barrels A and B are carried in a common cradle C. Each barrel is connected to one of the elements (D and E respectively) of a brake, the other element (the piston or cylinder) of which is connected to the common cradle.

In the illustrated example it is assumed that the cylinders F and G are formed in the cradle C, and that each of the barrels A, B is secured to a tubular piston rod (D, E) respectively. This rod D terminates in a movable head D¹ working liquid-tight in the cylinder F and constituting a diaphragm (d¹) around a counter rod f which is fixed to the bottom of the cylinder F and is formed at one end with a piston head working in the tubular rod D. The tubular rod E has likewise a piston head E¹ working liquid-tight in the cylinder G and constituting a diaphragm e¹ around a counter rod g along which the rod E moves that is carried by the bottom of the cylinder G. The two cylinders F and G communicate with each other at their rear ends through an orifice H.

It is assumed that the parts are in position shown in Figure 2, and the gun barrel A is loaded: then the firing of this barrel will cause a recoil of the combination A, D. This recoil will be braked by the forcing of the liquid through the diaphragm d¹. At the same time the piston head D¹ will force liquid to the rear through the orifice H against the piston head E¹ with the result that this piston head, and consequently the whole arrangement B, E is driven forwards. A portion of the energy of the recoil of the barrel A is thus utilized to run-out the barrel B. After the barrel A is fired, the parts assume finally the position shown in Figure 3.

If now the barrel B be fired, the same

effects will be produced, but inversely, and after the firing, the parts will assume the positions shown in Figure 2. The position of the centre of gravity of the moving system A—D—B—E remains approximately constant for the duration of the firing.

The improved gun of this invention may be mounted on a gun carriage of any known type. For travelling on the road the gun barrels may occupy either of the positions shown in Figures 2 and 3, or they may be moved into a position in which the rear end surfaces of their breeches are situated in one and the same plane, and they may be fixed in this position by means of a locking device.

Referring to the second embodiment of the invention, illustrated in Figs. 4 to 10 inclusive, the conjugated gun barrels A and B are likewise carried by a common cradle C. Each barrel is connected to a cylindrical rod (D and E respectively) slideable in a sheath (I and J respectively). This sheath has a head (I¹, J¹) serving as the piston of a brake whereof the cylinder (F, G) is carried by the cradle C. The two cylinders F, G are connected to each other at their rear ends by a duct K. Each of the barrels A, B carries further a tappet (A¹, B¹) for actuating the movable element of a recuperator of a spring or other type. In the illustrated example this recuperator comprises a cylinder L in which a rod M can slide, provided at its forward end with a head M¹ against which bears a spring N, and at its outer end with a mushroom head M² by which the said rod is moved alternately by the tappets A¹ and B¹.

It is assumed that the parts are in the position shown in Figure 6, and one of the barrels A is being fired, whereupon the recoil of this barrel will cause the rod D and sheath I to move together towards the rear. The recoil is braked by the throttling of the liquid in the cylinders F and G in its flow through a groove γ^1 in the sheath I which latter slides along a straight fillet F¹ on the inside surface of the cylinder F. At the same time the liquid forced towards the rear by the end of the tubular rod D and the rear end face of the sheath I acts upon the closed end E¹ of the rod E, and thus causes this rod, and consequently also the barrel B, to move in the forward direction. In this forward movement the barrel B carries along with it by means of the tappet B¹ the mushroom head M² of the rod M, thereby compressing the spring N, or, in other words, re-charging the recuperator. In this way the parts assume at first the position shown in Figure 7 when the recoil has ended. Then by the action of the expansion of the spring N, the barrel B is returned to the rear by the engagement of the tappet B¹ by the mushroom head M²;

the forcing of the liquid of the cylinder G into the cylinder F by the tubular rod E causing the barrel A to run out again, and thereby return the parts finally into the position shown in Figure 6.

70

If in starting from this position the barrel B be fired, the parts at the end of the recoil will have the position shown in Figure 8, after which the barrel A is run-in again by the action of the recuperator, whereas the barrel B is run out again by the forcing of the liquid out of the cylinder F and into the cylinder G, and the action of the liquid forced upon the combination E, J.

75

It is to be understood that each of the barrels A, B may be replaced by one or more groups each of two or more barrels, connected as a whole to a single recuperator brake. Or each group may have its own recuperator brake; the single recuperator brake of any one group being conjugated with the recuperator brake or brakes of the other group or groups by any one of the above described means or any other suitable manner.

80

It is likewise to be understood that it is not necessary to utilize the whole of the energy of the recoil of any one barrel or any one group of barrels for effecting the running out of the other barrel or other group of barrels, and that a part of such energy may be utilized in the known manner for effecting the automatic operation of the mechanisms for opening and closing the gun breeches, and for loading and firing the gun barrels.

95

The illustrated examples show what is considered to be the most practical method of effecting the conjugation of two gun barrels or of a group of gun barrels by means of a hydraulic recuperator-brake apparatus. The braking and recuperating apparatus however may be of any suitable type and the conjugation of the movements of the two barrels may be effected by means of devices of a purely mechanical, pneumatic, hydro-pneumatic, or other type.

100

105

Having now particularly described and ascertained the nature of my said invention and in what manner the same is to be performed, I declare that what I claim is:—

110

1. A multi-barrel gun comprising, in combination, an even plurality of barrels, a common cradle for said barrels, means including a rod and an apertured diaphragm having operative engagement with each of said barrels for braking the recoil of the latter, and means for transferring the energy of recoil of one barrel to the rod and diaphragm of an adjacent barrel for running out the latter, said rod and diaphragm having relative longitudinal movement during the recoil of the barrels.

120

125

2. A multi-barrel gun comprising, in com-

130

bination, conjugated barrels, a common cradle for said barrels having therein a pair of cylinders, means having operative engagement with each of said barrels in-

on said barrels for actuating the movable 45 element of said recuperator to recharge the latter during the running out of one of said barrels.

5. A multi-barrel gun comprising, in combination, a rod and a diaphragm positioned in each of said cylinders for braking the recoil of one barrel and simultaneously running out another of said barrels, said diaphragm being movably mounted in said cylinders and having relative longitudinal movement with said rod during recoil of the barrels.

6. A multi-barrel gun comprising, in combination, an even plurality of barrels, a cradle for said barrels having cylinders formed therein, said cylinders being in communication with each other, a sheath slidably mounted in each of said cylinders, a rod connected to each of said barrels and ex- 55 tending within said sheaths, a spring recuperator secured to said cradle, tappets movable with said barrels for actuating the movable element of said recuperator to recharge the latter during the running out of 60 one of said barrels, said recuperator being adapted to return the running out barrel back to its departure position, and to return the barrel which has just recoiled to its departure position.

15. A multi-barrel gun comprising, in combination, an even plurality of recoiling barrels, cylinders positioned adjacent said barrels, a diaphragm slidably mounted in each of said cylinders, a rod secured to each of said barrels and normally extending within said cylinders, a recuperator positioned adjacent said barrels, and tappets secured to said barrels to engage the movable element of said recuperator during the running out of said barrels.

7. A multi-barrel gun comprising, in combination, a cradle, an even plurality of guns mounted in said cradle and normally having their muzzles in alignment, means for braking the recoil of said barrels and simultaneously running out at least one of said barrels, said means including a rod and a sheath, one of said last named elements being connected to said cradle and the other of said elements to one of said barrels, tappets rigidly secured to said barrels, and a recuperator including a movable element, said last named element having engagement with said tappets for returning said barrels to their normal position of alignment after 80 recoil and running out.

20. A multi-barrel gun comprising, in combination, a cradle, an even plurality of barrels mounted in said cradle the breech of said barrels being normally in the same vertical plane, means for braking the recoil of said barrels and for simultaneously 70 running out one of said barrels, tappets on said barrels, and a recuperator having engagement with said tappets and adapted to be energized by the recoil of one of the barrels for returning the latter to their normal 75 position of alignment.

25. A multi-barrel gun comprising, in combination, an even plurality of barrels, a cradle for said barrels having cylinders formed therein, said cylinders being in communication with each other, a sheath slidably mounted in each of said cylinders, a rod connected to each of said barrels and extending within said sheaths, a recuperator secured to said cradle, and tappets mounted

80. Dated this 23rd day of November, 1923.
In testimony whereof I have signed this specification.
